UNITED STATES PATENT OFFICE.

DAVIS MARINSKY, OF NEW YORK, N. Y.

WAIST-BELT.

971,766.

Specification of Letters Patent.

Patented Oct. 4, 1910.

Application filed December 23, 1909. Serial No. 534,622.

To all whom it may concern:

Be it known that I, DAVIS MARINSKY, a citizen of the United States, and residing at New York, in the county of New York and 5 State of New York, have invented certain new and useful Improvements in Waist-Belts, of which the following is a specification, such as will enable those skilled in the art to which it appertains to make and use 10 the same.

This invention relates to belts designed for use in connection with shirtwaists and similar garments, and the object thereof is to provide an improved belt of this class which 15 is designed to draw the shirtwaist together at the back and make it fit tightly at the front, and which is also designed to support a skirt.

The invention is fully disclosed in the following specification, of which the accompanying drawing forms a part, in which the separate parts of my improvement are designated by suitable reference characters in each 20 of the views, and in which;—

25 Figure 1 is a sectional plan view showing my improved waist belt and the method of securing it to a shirtwaist and means for connecting the waistband of the skirt therewith; Fig. 2 a view similar to Fig. 1 but 30 showing the device as used; Fig. 3 a back view of the band forming the belt and showing hooks for supporting a skirt connected therewith; Fig. 4 a side view of an attachment which is connected with the belt, 35 and;—Fig. 5 a similar view of another attachment which is used in connection with that shown in Fig. 4.

In the drawing forming part of this specification, I have shown at *a* a section of the 40 waistband of a shirtwaist and at *b* the waistband of a skirt, and in the practice of my invention I provide a belt *c* of any suitable material, preferably textile material, and I also provide two flexible strips *d* and *e* composed of celluloid, rubber, metal or any other 45 suitable material. The strip *d*, in the form of construction shown, is provided with an enlarged head or end *d*² having a transverse slot *d*³, and the strip *e* is provided with an 50 enlarged head or end *e*² having two transverse slots *e*³ and *e*⁴, the enlarged head or end *d*² of the strip *d* is also provided in the outer 55 end portion thereof with a recess *d*⁴ inwardly of which is secured an elastic loop *d*⁵ while the corresponding part of the strip *e*.

is provided with a recess *e*⁵ inwardly of which is secured an elastic loop *e*⁶. In practice, the strip *e* is passed through the transverse slot *d*³ in the part *d* as indicated in Fig. 1, and said part *d* is passed through the 60 slots *e*³ and *e*⁴ in the part *e* as is also indicated in said figure. I also secure to the waist band *a* of the shirtwaist buttons *f* and *g*, said buttons being provided, in the form of construction shown with shanks, and it 65 will be understood that when the parts *d* and *e* are connected in the manner described, they are free to slide one upon another and the belt *c* is secured to the end portions *d*⁶ and *e*⁷ of the parts *d* and *e* at *d*⁷ and *e*⁸, said 70 parts being provided with holes *d*⁸ and *d*⁹ for this purpose.

In connecting the device with the waistband of the shirtwaist at the back the outer end portions *d*⁸ and *e*⁷ of the parts *d* and *e* 75 are forced together or inwardly and this operation separates the end portions *d*² and *e*² of said parts, and the elastic loops *d*⁵ and *e*⁶ are then engaged with the buttons *f* and *g* on the waistband *a* of the shirtwaist. A 80 pull is then exerted on the end portions of the belt *c* and this pull draws the end portions *d*² and *e*² of the parts *d* and *e* together and contracts the waistband of the shirtwaist as shown at *a*² in Fig. 2, and this 85 operation tightens the said waistband of the shirtwaist at the front, and the end portions *c*² and *c*³ of the belt *c* may be connected at the front by means of a buckle *c*⁴ if desired, or in any other preferred manner. 90

The belt *c* or the band from which said belt is formed is provided centrally thereof with engaging devices *h*, with which the waistband *b* of a skirt is adapted to be connected, and these engaging devices in the 95 form of construction shown consist of eyelets provided with upwardly directed prongs or teeth *h*², but said engaging device may be of any desired construction.

By means of my improvement I provide a 100 belt which is adapted to be connected with the waistband of a shirtwaist at the back and to be secured at the front, said belt being provided with means whereby the shirtwaist band may be drawn together at the 105 back and also with means whereby a skirt may be supported at the waist and held in proper position with reference to the shirtwaist; and changes in and modifications of the construction herein described may be 110

made, within the scope of the appended claim, without departing from the spirit of my invention or sacrificing its advantages.

It will be understood that the buttons *f* and *g* when the device is in use, or the shanks thereof fit in the recesses *d*⁴ and *e*⁵ in the opposite ends of the flexible strips *d* and *e* and the elastic loops *d*⁵ and *e*⁶ hold said parts in this position and also hold the end portions *d*² and *e*² of the parts *d* and *e* against lateral or vertical movement.

Having fully described my invention, what I claim as new, and desire to secure by Letters Patent, is;—

15 A belt provided with two elastic strips one end of each of which is enlarged, the enlarged end of one of said strips being provided with a transverse slot and the enlarged end of the other with two transverse

slots, the smaller end portion of one of said strips being passed through the transverse slot in the enlarged end of the other, and the smaller end of the last named strip being passed through both of the slots in the enlarged end of the other strip, and the smaller ends of both of said strips being secured to the inner side of said belt, and means whereby the larger ends of both of said strips may be connected with the waist band of a waist at predetermined points. 30

In testimony that I claim the foregoing as my invention I have signed my name in presence of the subscribing witnesses this 21st day of December 1909.

DAVIS MARINSKY.
